NAIL

Filed Sept. 27, 1928

Inventor
Fred Foos

By Clarence O'Brien
Attorney

UNITED STATES PATENT OFFICE

FRED FOOS, OF SAN FERNANDO, CALIFORNIA

NAIL

Application filed September 27, 1928. Serial No. 308,817.

My invention relates to improvements in nails and aims to provide means throughout its shank to prevent the creeping upwardly or accidental displacement of the same after the nail has been driven into the wood.

Another object of my invention is the provision of a nail which can be manufactured at approximately the same cost as the ordinary nail in common use and serves as a very efficient improvement thereon.

With these and other objects in view the present invention consists in its novel features as will be hereinafter more fully described and shown in the accompanying drawings, it being understood that changes in the form, proportion, size and minor details may be made within the spirit and scope of the appended claim without sacrificing the advantages of my invention.

20 In the drawing:

The figure is an enlarged perspective of the improved nail.

With particular reference to the drawing numeral 1 indicates generally a nail having a shank 2, said shank having a head 3 formed at one end and a point 4 at its opposite end.

The shank is of an increased thickness at a point intermediate the head and point and preferably a little below the center of the shank. At opposed points longitudinally extending notches 5 are formed in the thickened portion of the shank to provide spaced shoulders 6-6 at opposite sides of the nail. At the end of these shoulders the surface of the thickened portion gradually merges into the surface of the nail shank to facilitate driving and releasing of the nail into and from the wood.

At opposite ends of said enlargement the shank is formed with a plurality of substantially V-shaped notches 7 in spaced relation and extending downwardly with respect to said shank 2.

It will thus be seen that a nail constructed in accordance with my invention is an improvement over the common nail now in use including certain advantages readily understood by all conversant with this art and clearly indicating that when the nail is driven home, the fibers of the wood will ex-

pand during the driving operation and contract after completion of the same so that the fibers will settle between the shoulders 6-6 and in the strips between the bars on said shank.

It is to be understood that the form of my invention herein shown and described is to be taken as the preferred example of the same and the various changes in the shape, size and arrangement of the parts may be resorted to without departing from the spirit of the invention or the scope of the subjoined claim.

Having thus described my invention, what I claim as new is:

A nail comprising a shank having a head on one end and a point on the opposite end, an enlarged portion intermediate said ends, said enlarged portion having at its medial point longitudinal notches on opposed sides of the shank, shoulders forming the boundaries of such notches and a plurality of V-shaped notches formed on the shank at opposite ends of said longitudinally extending notches.

In testimony whereof I affix my signature.

FRED FOOS.
